ATTORNEYS

UNITED STATES PATENT OFFICE

EDWARD G. SCHAEFFER, OF BROOKLYN, NEW YORK, ASSIGNOR TO AMERICAN CHARACTER DOLL CO., INC., OF NEW YORK, N. Y., A CORPORATION OF NEW YORK

JOINT

Application filed March 11, 1932. Serial No. 598,241.

This invention relates to a joint or articulation between two main parts or members of a doll to join said parts or members and also allowing a certain movement thereof.

5 An object of the invention is the provision of a simple, inexpensive and efficient joint or articulation of such character that the parts or members, constructed preferably of rubber, may be joined or connected together 10 for relative movement.

The nature of the invention and its distinguishing features and advantages will appear when the following specification is read in connection with the accompanying drawing, in which

15 Figure 1 is a front view of a doll, shown partly in elevation and partly in section, embodying the features of the invention;

Figure 2 is a view of a portion of one of 20 the parts or members of the doll detached.

Referring now more particularly to the drawing, it will be apparent that there has been shown a doll consisting of separate main parts consisting of a hollow body 10, a hollow 25 head 11, arms 12, and legs 13. All of these parts in the present instance are made of soft rubber. The head, arms and legs are joined to the body 10 for relative movement by substantially similar means. The said

30 means joining the head 11 with the body 10 consists of an inwardly directed, substantially annular section 14 in the neck opening. The body 10 has a neck section 15 which conforms to and fits in the annular section 14.

35 A button 16 is secured to the neck section 15, and this is accomplished by the provision of a shank 17 on the button which is cemented or otherwise secured in the neck section 15.

It is to be understood that the button 16 40 may be formed integral with the neck section 15 which may be of solid construction. The button 16 being made of rubber may be temporarily deformed sufficiently to be passed through the opening provided by the

45 section 14 and brought into engagement with the neck section 15. It will be apparent that the button 16 is of mushroom formation so that the marginal portion will embrace or surround the annular section 14 of the 50 head 11.

Each of the arms 12 and legs 13 is joined to the body 10 by means which is substantially similar to that described above. Each arm 12 and leg 13 has a button 18 and shank 19 integral therewith, the latter being disposed between the main section of the arm or leg, as the case may be, and the button 18. The body 10 has a hole or opening 20 for each arm and leg. That portion of the body 55 surrounding the hole or opening 20, and the button 18 of the arm or leg relating thereto may be deformed sufficiently to pass the button through the hole or opening 20 to dispose the button 18 on the inside of the body 10 in engagement therewith. It will be apparent 60 that the wall of the body 10 will be disposed between the button 18 and the main section of the arm or leg, as the case may be. In this manner each arm or leg will be joined or be articulated with the body 10 and will 70 be movable in relation thereto. It is to be understood that, instead of forming the button 18 and shank 19 integral with each arm 12 or leg 13, the shank 19 may be integral 75 with the button 18 and also be of such length as to be secured or cemented in a socket in the main section of the arm or leg, as exemplified by the securing of the button 16 joining the head 11 with the body 10.

It is to be understood that the body 10 and 80 the head 11 and its neck section 14 need not be made of rubber, and that it may be made of suitable rigid material used for the construction of doll parts, since the buttons being made of resilient material may be deformed, 85 which is all that is required, to engage the buttons to join or articulate the parts.

I claim:

1. A joint between two main parts of a doll, one of said parts having an inwardly 90 directed substantially annular section opening into the interior of said part, and said part also being hollow, and the other part having a section conforming to and fitting in said annular section and an annular flange 95 on said second section disposed within said hollow part and having its marginal portion in engagement with said annular section, said annular flange being made of rubber in order to be temporarily deformed sufficiently to be 100

passed through the annular section and engaged as aforesaid, to join said parts.

2. The invention defined in claim 1, in which the annular section is made of rubber.

5 3. The invention defined in claim 1, in which the annular flange is carried by a shank secured to said section fitting in said annular section.

4. A joint between two main parts of a
10 doll, one of said parts having an inwardly directed substantially annular section opening into the interior of said part and said part also being hollow, and the other part having a section conforming to and fitting
15 in said annular section and an annular flange on said second section disposed within said hollow part, and having a depending annular rim in engagement with said annular section, said annular flange being made of rubber in
20 order to be temporarily deformed sufficiently to be passed through the annular section and engaged as aforesaid to join said parts.

EDWARD G. SCHAEFFER.
